US00D687193S

(12) **United States Design Patent**
Wenstrand(10) **Patent No.:** **US D687,193 S**
(45) **Date of Patent:** **** Jul. 30, 2013**(54) **COMBINATION FEEDER AND PESTICIDE APPLICATOR**(75) Inventor: **Thomas Wenstrand**, Mt. Pleasant, IA (US)(73) Assignee: **Hawkeye Steel Products, Inc.**, Houghton, IA (US)(***) Term: **14 Years**(21) Appl. No.: **29/380,081**(22) Filed: **Nov. 30, 2010**(51) LOC (9) Cl. **30-03**

(52) U.S. Cl.

USPC ..... **D30/131**; D30/121; D30/128(58) **Field of Classification Search**

(57) **CLAIM**

The ornamental design for a combination feeder and pesticide applicator.

DESCRIPTION

FIG. 1 is a perspective view of a combination feeder and pesticide applicator;

FIG. 2 is a top view thereof;

FIG. 3 is a bottom view thereof;

FIG. 4 is a front-side view thereof, the back-side view being identical to the front-side view; and,

FIG. 5 is a left-side view thereof, the right-side view being identical to the left-side view.

The broken lines and portions contained within broken line are not claimed.
